UNITED STATES PATENT OFFICE.

DONALD E. WILLARD, OF DANVILLE, ILLINOIS.

DOOR-HANGER.

1,155,390.

Specification of Letters Patent.

Patented Oct. 5, 1915.

Application filed July 6, 1915. Serial No. 38,098.

To all whom it may concern:

Be it known that I, DONALD E. WILLARD, a citizen of the United States, residing in Danville, county of Vermilion, State of Illinois, have invented certain new and useful Improvements in Door-Hangers, of which the following is a specification.

My invention relates to hangers for sliding doors and more particularly to that class of doors that are opened and closed by a combination of sliding and folding movements and which are commonly termed "accordion doors." These doors are generally arranged in two sets, each set comprising a plurality of doors horizontally connected together, the base member being hinged to a door post. So arranged, these doors may be made to close a wide space and because of their number and weight and the plurality of movements by which they are operated, they require specially-adapted hangers not only adequate to support the weight, but of such construction that the folding and sliding movement of the doors may be accomplished without edgewise tilting of the doors themselves and without undue friction due to twisting or displacement of the hangers.

To these ends I have provided a special form of hanger which is of the trolley type; that is, it has two pairs of track wheels mounted in tandem on a rigid frame, the frame supporting a pendant member to be connected to the upper edges of the doors. This construction necessitates two trackways. This track may be of any desired form. I have chosen, for the purpose of illustration, a sheet metal track of rectangular tubular form having its lower wall severed and the opposed edges upturned to provide parallel trackways.

Other features of my invention relate to the construction and arrangement of the suspension bolt or pendant member and to the provision of guide rollers for preventing the twisting or wedging of the track wheels in the tracks.

Another feature of my invention relates to the provision of a suitable anti-friction bearing on which the door is supported and turns.

In the accompanying drawings—Figure 1 is a side view of the hanger proper showing the upper edge of the door in section. Fig. 2 is an end view of the hanger showing the track in section, the supporting flange of the hanger being broken away. Fig. 3 is

likewise an end elevation of the hanger showing parts thereof in vertical section. Fig. 4 illustrates a modified application of the hanger to the corner of the door. Fig. 5 is an elevation showing the two sets of doors, one set being folded and a portion of the framework above the doorway being broken away. Figs. 5^A and 5^B are diagrammatic views in plan, Fig. 5^A showing the doors extended and Fig. 5^B showing the doors folded, the dotted lines showing the intermediate positions.

In the drawings 6 represents the track which is composed of sheet metal and which is of substantially rectangular tubular form, the edges of the sheet being upturned as at 8 to provide the trackways 9. This track is supported in a bracket member 7 having a horizontal attaching flange 7^a. The hanger is in the form of a rigid open casting 10 in which is journaled the track wheels 11 on shafts 12 which are mounted in bearings or journals in the upper outer corners of said frame 10 and are provided preferably with balls or rollers 13. The hanger body 10 has the top bar 14, bottom bar 16, and side bars 15, 17. Bottom bar 16 is provided with an enlarged opening 19 surrounded by a cup-shaped casing having the bottom wall 20 and the side walls 21.

22 represents a bushing provided in an enlarged aperture in the top bar 14, the opening between the walls 23 of the top bar 14 being of such width as to permit the insertion of the suspension bolt 24. The lower portion of the latter is threaded and the portion 25 is enlarged into a bearing member or shoulder 26 while its upper end is reduced as shown at 27 and is fitted to the bushing 22. Within the cup casing is mounted the raceway 30 containing ball bearings 31, the raceway being provided with a cover plate 32 and the downwardly-projecting flange 33. It will be seen that the suspension bolt takes bearing by the shoulder 26 on the anti-friction element so that the weight of the doors is transferred thereto, and that the bolt has an enlarged shoulder 34 which bears upon the bushing element 22. The casting 10 is also provided with the lugs 35 on the side bars 15, 17, in which are journaled vertically-disposed rollers 36. A plate 37 is secured to the top edges of the doors and has a threaded aperture through which the suspension bolt 24 passes.

38 represents the wood screws for securing the plate to the edge of the door which is preferably let into a recess 39 in the edge of the door, the latter being also provided with the vertical socket or recess 40 into which the end of the suspension bolt 24 works.

41 represents a lock nut by means of which the suspension bolt is adjustably secured against rotation in the plate 37.

The sides of the threaded portion of the bolt 24 are preferably flattened as shown at 42 to permit of the application of a suitable tool for turning the bolt in the threads of the plate.

It will be observed that the suspension bolt or pendant is connected to the casting or body of the hanger intermediate the axles of the wheels and that the weight carried thereby is supported on the anti-friction bearing mounted upon the lower bar or member of the hanger body, and that the suspension bolt or pendant also has a bearing in the top bar of the hanger. From this it results that the weight of the doors is supported well below the wheels and that the doors and bolt member swivel freely on the anti-friction bearing in the bottom member of the hanger body, while the suspension bolt also has a bearing in the top cross-bar of the hanger which thus serves as the driving member of the hanger when the door is being opened or closed. Thus friction in the turning or folding movement of the doors is largely reduced and the weight being carried well below the wheels tends to keep the latter in contact with the track and prevents edgewise tilting, while the bearing of the suspension bolt in the upper cross-bar likewise tends to steady the action.

The function of the vertical rollers 36 is to prevent the twisting of the hanger in the trackways and to insure their moving in right lines. For this purpose the rollers 36 are disposed on opposite sides of the hanger and are so disposed as to contact with the trackways should any twisting tendency develop. A further purpose subserved by these rollers is to counteract thrust at an angle to the plane of the door from whatever cause, such as wind pressure and cramping due to the opening and closing of the doors.

I am aware that it is not new to employ steady or thrust rollers, but it is desirable with a construction such as I have illustrated to provide against thrust in either direction, and while I have shown rollers arranged in pairs for this purpose it is obvious that a single roller placed between, making contact with the trackways on either side would serve the purpose.

In Fig. 4 I have shown a slightly modified construction in which the hanger is connected to the corner of the door instead of

at an intermediate point between its edges. In this case the suspension plate 43 is of angle form and is secured to the top and one side edge of the door, the latter being notched in its vertical edge 45 to receive the suspension bolt and recessed on its upper edge as at 46 to receive the plate. The same form of construction may be employed for suspending the door near one edge by providing an aperture as shown at 50 to receive the stem of the bolt. An anchor 47 may be let into the door and provided with an aperture 48 to receive the fastening or anchor pin 49.

As shown in Fig. 5 the doors A are arranged in two sets each comprising three main doors A and a base member B, the latter being hinged to the door posts. The upper frame of the door between the points C—D is broken away to show the application of the hanger but as this will vary with the different situations it need not be particularly described. It will be sufficient ordinarily to apply a hanger to each alternate door as shown in Fig. 5 and with the construction which I have described it will be found that these hangers are adapted to support any number or weight of doors desirably used. The provision of a suspension bolt with a threaded shank, a suspension plate and lock nut affords a ready means of adjusting and alining the parts without interfering in any way with the free swivel movement of the suspension bolt and the doors upon the hanger.

While I have shown a track of peculiar type, it is obvious that other constructions of track, such as the well-known tubular type, may be used, in which case the form of the bracket may be modified accordingly.

It is within the scope of my invention to modify the structure particularly with relation to the location of the antifriction or swivel bearing since the essential characteristic of my invention is the provision of a hanger which is adapted to permit the swiveling movement and also will afford a rigid driving connection between the bolt and the hanger body. I have shown the antifriction bearing located in the bottom bar or member of the hanger and the driving connection of the bolt in the upper member or bar of the hanger body, but this might be reversed and the antifriction bearing placed in the top bar of the hanger and the driving connection in the bottom bar of the hanger.

I am aware that it has been proposed to employ a swiveling or antifriction connection and a driving connection located in the same, or approximately the same, plane—in other words to apply the driving connection to the turning member of the antifriction bearing, but my invention is distinguished from this in that the swivel connection and the driving connection are separated from

each other and therefore avoids the tilting or rocking of the rotatable member of the antifriction bearing.

I claim:

5 1. A hanger for sliding folding doors comprising a hanger frame, track wheels, and a suspension bolt, the latter having driving connection with the hanger frame at its upper portion and a bearing support 10 upon the hanger frame below the track wheels, substantially as described.

2. A door hanger comprising in combination a hanger frame, two pairs of track wheels mounted thereon in tandem, a track 15 member having two separated parallel trackways, a suspension member rotatably mounted in the hanger frame and having a horizontally-disposed swivel bearing therein, and a driving connection therewith, the 20 swivel bearing and the driving connection being separated from each other and the suspension member being adapted for connection to the door, substantially as described.

25 3. A door hanger comprising in combination a hanger frame having upper and lower frame elements, two pairs of track wheels journaled in said frame, a suspension member rotatably mounted within the frame and 30 having a bearing in the upper of the frame members, the lower frame member having a horizontally-disposed antifriction bearing and the suspension member resting thereon, means for connecting the door to the suspension member, and means for locking the suspension member with relation to the door, substantially as described.

4. A door hanger having a hanger frame, two pairs of wheels mounted therein in tandem relation, a track having separated trackways for the wheels, a suspension element 40 rotatably mounted in the hanger frame and depending between said trackways and having separate driving and swiveling connections with the frame, and steady rollers 45 mounted on the frame and adapted to engage the track ways.

5. An adjustable door hanger comprising

a rigid frame, two pairs of wheels in tandem carried by said frame, an attaching plate adapted to be secured to a door and provided with an aperture therethrough, a suspension bolt rotatably mounted in the frame and provided with separated driving and swiveling connections therewith and 55 having a threaded connection with the attaching plate, and a lock nut applied to the suspension bolt whereby to prevent rotative movement of same with respect to said plate when adjusted.

6. In a hanger for accordion doors the combination with parallel trackways of a hanger comprising a rigid body and two pairs of wheels adapted to travel on said tracks, a vertical suspension bolt rotatably 65 mounted in the hanger body and having a driving connection with said body above the journals of the track wheels and an antifriction bearing for the suspension bolt located below the axis of the track wheels and 70 on which the bolt is adapted to turn, substantially as described.

7. In a device of the class described the combination with spaced apart parallel track ways of a hanger having track wheels 75 adapted to travel on said track, a suspension member rotatably mounted in the hanger between the pairs of wheels and having an antifriction bearing on the hanger body below the track wheels, and vertical rollers 80 disposed on opposite sides of the suspension member and adapted to contact the edges of the trackways, substantially as described.

8. A hanger for accordion doors comprising a rigid hanger body, two pairs of wheels 85 mounted in tandem near the ends of said body, a suspension bolt rotatably engaging the hanger above the wheel axles and depending therebetween and having an antifriction bearing on the hanger body below 90 the wheel axles.
